UNITED STATES PATENT OFFICE.

HENRY BRESSER, OF TOLEDO, OHIO.

BLOCK-MOLD.

No. 908,944.

Specification of Letters Patent.

Patented Jan. 5, 1909.

Application filed May 13, 1908. Serial No. 432,624.

To all whom it may concern:

Be it known that I, HENRY BRESSER, a citizen of the United States, and a resident of Toledo, in the county of Lucas and State of Ohio, have invented a new and Improved Block-Mold, of which the following is a full, clear, and exact description.

This invention relates to ornamental block molds, and is intended especially to be used in forming the markers employed in graveyards for indicating the division of the lots, the position of walks, etc. While the invention is particularly adapted for this purpose, it is capable of general use where blocks are to be molded, having inscriptions or characters in the faces thereof.

The invention consists in the construction and combination of parts to be more fully described hereinafter and particularly set forth in the claims.

Reference is to be had to the accompanying drawings forming a part of this specification in which similar characters of reference indicate corresponding parts in all the figures.

Figure 1 is a plan showing a finished block and the manner in which it is used to indicate the position of a lot, divisions of parts of the lot, and so on; Fig. 2 is a plan showing the inner face of the cap or cover of the mold; Fig. 3 is a vertical cross section through the mold, and showing the same filled with composition or cement in the molding operation, this view particularly illustrating the means for retaining the letters or characters in the cover which are to impress the face of the block; and Fig. 4 is a top plan view of a portion of the cover of the mold, and illustrating further the means for holding the letters or characters on the cover, which are to be impressed in the block.

Referring more particularly to the parts, 1 represents the body or box of a mold, which is of rectangular or square form, as shown. This box is partly filled with composition 2 of cement, or similar material, which is to form the block, which while in a plastic state, is impressed by the cover 3, carrying the type 4. This cover 3 fits the horizontal cross section of the box so that it may seat in the box in such a way that it may be supported on the composition within the box. On its under face the cover or cap 3 is formed with downwardly projecting lips 5 which are rounded, as shown, so as

to produce a rounded upper edge for the finished block, as will be readily understood. On the under face of the cap or cover 3, two ribs 6 and 7 are formed at right angles to each other, the ribs 7 being parallel with the direction of the reading lines of the type. The rib 6 meets the rib 7 near the middle point thereof, and these ribs are of V-form, as indicated in Fig. 3.

The cover 3 is provided with a plurality of openings 8, which are disposed a slight distance apart according to the spacing of the type used. These openings 8 are preferably elongated vertically, that is, longitudinally of each type or figure, and the ends are rounded so that the openings may be considered as of oval form. In these openings, letter blocks 9 are received in the manner indicated in Fig. 4. These blocks 75 are of oblong form so as to fit the openings which receive them, and they are provided at opposite points on their side faces, with recesses or small grooves 10, which assist in retaining the letter blocks when placed in 80 position. In order to further retain the letter blocks, between the openings 8 pockets 11 are formed in the rear or upper face of the cover. The sides of these pockets have deep notches or recesses 12, which communicate with the openings, as will be readily understood, and in this way, an upwardly projecting post 13 is formed in each pocket. On the upper ends of these posts 13, spring plates 14 are attached respectively, by screws 90 15, as indicated. These spring plates 14 extend downwardly at their edges and are formed with rounded beads or nibs 16, which project slightly into the openings 8. These beads or nibs 16 constitute shoes 95 which are adapted to be engaged in the grooves 10 in the sides of the letter blocks so as to retain the blocks when they are shoved into the cover from the forward or under side thereof. When the letter 100 blocks are in position in the cover as described, their lower faces are flush with the lower faces of the cover, and this is a necessary arrangement in order to insure that the faces of the molded block between the type 105 will remain smooth and unbroken. The type 4 are attached to the under faces of the letter blocks and project beyond the edges of the openings 8 so that they extend under the lower faces of the cover 3. From this 110 arrangement it will be evident that when pressure is brought upon the cover to impress

the plastic block, the full force of the pressure will come upon the type. These type are preferably formed of V-shaped ribs which cut into the face of the mold and impress it very readily. In practice, in addition to the ribs 6 and 7 which indicate the lines of divisions of the lots, the cover may have permanently attached type such as the type 17. It is only necessary that the 10 part of the inscription which is to be changed shall have the arrangement described for securing the type on the cover. In this way the same cover may be used for molding the blocks which are used in all the different 15 parts of the cemetery.

The manner of using the block is indicated in Fig. 1, where it will be seen that the rib 7 indicates the line of the walk or the main division line of the lots, while the rib 20 6 will point out the position of the dividing line between two adjacent lots. Attention is called to the fact that on account of the arrangement for mounting the type on the cover the retaining spring plates are relieved of all pressure, that is, the pressure which impresses the type into the face of the block is not received by the type through the retaining means, but directly from the cover. 25

It will be evident that while the mold is intended for the purpose particularly described, it may be used for other special purposes where plastic blocks are to be molded with different inscriptions or characters on the faces.

Having thus described my invention, I claim as new and desire to secure by Letters Patent,—

1. A plastic block mold having an impressing cover with openings therein, letter

blocks received in said openings, adapted to 40 be inserted from the front and having their faces flush with the inner face of said cover, resilient retaining means for said letter blocks, and type attached to said letter blocks and projecting beyond the edge of 45 said openings to receive the pressure from said cover.

2. A plastic block mold having a cover with a plurality of openings therein, letter blocks received in said openings and having 50 type on the lower faces thereof projecting beyond the edges of said openings, and resilient retaining devices carried by said cover and engaging said letter blocks.

3. A plastic block mold, a cover with a 55 plurality of openings therein, letter blocks received in said openings, type carried by the under faces of said blocks and receiving pressure directly from said cover, and retaining devices attached to said cover, 60 engaging the side faces of said blocks and retaining the same.

4. A plastic block mold having a cover with a plurality of openings therein, spaced apart, pockets formed between said openings, spring plates fastened in said pockets and having shoes projecting in said openings, and letter blocks fitting in said openings and engaging said shoes to be retained thereby, said letter blocks having type on 70 the lower faces thereof.

In testimony whereof I have signed my name to this specification in the presence of two subscribing witnesses.

HENRY BRESSER.
